Primary Examiner — Messina L Smith

(57) **CLAIM**

The ornamental design for an AIR FRYER, as shown and described.

DESCRIPTION

FIG. 1 is a front view of an AIR FRYER, showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and

FIG. 8 is another perspective view thereof.

The broken lines and areas within depict portions of the Air Fryer that form no part of the claimed design.

1 Claim, 8 Drawing Sheets
